UNITED STATES PATENT OFFICE.

JOHN R. DAVIS, JR., OF NEENAH, WISCONSIN.

CHOP-GRADER.

SPECIFICATION forming part of Letters Patent No. 380,096, dated March 27, 1888.

Application filed February 8, 1881. Serial No. 25,727. (No model.)

To all whom it may concern:

Be it known that I, JOHN R. DAVIS, Jr., of Neenah, in the county of Winnebago and State of Wisconsin, have invented certain new and useful Improvements in Chop - Graders, of which the following is a specification.

Chop or meal as it comes from the reducing apparatus is generally carried to bolting-reels, which take out the flour and send the middlings and impurities on to the purifier. In passing through these reels the material is repeatedly tumbled together and against the sides of the reel, and as a consequence a large amount of dust is worn from the particles, both from the good and from the impure and is mixed together, passing into the flour and middlings and lowering their standard. In order to overcome this objection and obtain a greater per cent. of purified middlings and a better grade of break flour, I have heretofore proposed to subject chop or meal to air-blasts as it comes from the reducing mechanism, whereby the flour is separated from the middlings and carried to the bolts, while the middlings go direct to the purifier, and have made application for Letters Patent for this process and for a machine by which it may be carried into effect.

My present invention is designed to furnish an improved machine adapted to separating, grading, and purifying according to said process, while at the same time capable of use in other grading and purifying operations; and it consists in arrangements of mechanism whereby air-currents of controllable intensity may be drawn transversely through the material falling upon the screen and transversely through the material falling into the chest, and in combinations and details of construction hereinafter described and claimed. In its preferable form I combine with the other instrumentalities of this machine a set or sets of reducing - rolls—such, for instance, as the Stevens roller-mill—so arranged as to discharge the chop at the head; but it will be understood that these rolls may be replaced by a hopper, and that the chop may be received from reducing mechanism of any appropriate form and system and located at any desirable distance.

In the drawings, Figure 1 is a perspective view of a machine embodying my invention.

Fig. 2 is a vertical section lengthwise thereof; Fig. 3, a front elevation, and Fig. 4 a modification.

55

A is a strong frame provided with bearings for the grinding-rolls B, feed-roller C, and adjusting devices D, and also supporting the domed mill-casing E and hopper E', these parts being constructed and arranged substantially as in the Stevens mill now well known in the market.

The mechanism for separating and grading the chop is contained within a casing, F, which fits snugly between the legs of the mill-frame and against the bearing-sills a, to the webs of which it may be bolted. A screen, G, covered with graded wire or silk cloth is arranged within this casing, as shown, so as to practically bisect its chamber. This screen may be reciprocated forward and backward like a shaker, or can be shaken sidewise at right angles to the course of the material thereon, or can be fixed in the case so as to be stationary.

In the present construction I have shown the screen as stationary, which I deem preferable. When so arranged, it will be set at a sufficient angle or incline to cause the chop falling upon its head to gravitate over the length until it reaches the tail. In order to clear the meshes, should there be a tendency to clog, a hammer or hammers, b, may be employed pivoted to the frame-work, and each operated by a tappet or cam, c, on a driven shaft, c', to strike at regular intervals against the tail-piece of the screen. The blows of the hammers will also tend to feed the material forward from the head, and therefore, when they are employed, the slope of the screen may be lessened, if desired.

90

The flaring compartment H, formed by the increased portion between the screen and the rolls, is open to the external air at its outer or larger end, and at its inner end, at the rear of the machine just beyond the head of the screen, connects, by means of a throat, d, and adjustable gate d', with a vertical air-trunk, I, leading to the suction-chamber I' at the foot of the machine. As the chop falls from the rolls, it strikes in succession the inner inclined faces of a series of horizontal slats, e, the uppermost of which lies partly beneath the outer roll, and is by them conducted to the head of the screen. The slats in the aggregate form a par-

95

100

tion in the compartment H, dividing off a sub-compartment, h, through which the chop passes, as above stated, to reach the screen, and which may be termed the "chop-chamber." The spaces between the slats form air-ports, one above the other, through which currents of air traversing the stream of chop may be induced by the fan or fans K, mounted in a suitable casing in the suction-chamber and 10 discharging into the dust-room.

Each air-port is provided with an adjustable gate, f, whereby the currents may be cut off or modified at any point in the height of the partition, and it will be understood that by 15 means of the gate d' in the throat d they may be moderated as a whole, or entirely stopped at any time. By this arrangement the flour and fine dust may be separated from the chop in its fall, leaving only middlings and a modi- 20 cum of impurities to pass over the screen and be separated into grades.

Beneath the screen is a chest, H', subdivided at its bottom into two or more pockets, h' h'', each with its appropriate duct or spout. A gate 25 or gates, g, as usual in similar chests, permits the receiving-area of these pockets to be varied at will, in order to modify the character of the grades deposited therein. At its outer end, beneath the tail of the screen, the chest 30 communicates with the external air by means of air-ports i, formed by a series of horizontal slats, the inner faces of which are advisably inclined to guard the falling material from escape. These air-ports, like those in the par- 35 tition above the screen, are each provided with adjustable gates i', whereby air-currents drawn through them may be moderated or cut off at any point in their height. At its inner end the chest H' communicates through the throat 40 k with the suction-chamber I'. An adjustable gate, k', serves to limit the size of the throat, or close it altogether, and thereby moderate or shut off the draft through the chest.

An inclined board, l, beneath the head of 45 the screen, serves to direct material deflected over said head by the upper air-currents, or, passing through the first meshes, into the chest H', and also to cut off the lower draft from the chop-chamber. A diaphragm, m, above the 50 screen forms a floor to the main upper compartment, H, and shuts off the air-current passing therethrough from the current or currents through the chest H'. This diaphragm may be a board, which I prefer shall be removable to 55 permit the draft at any time to be turned downward through the screen into the chest, or upward through the screen into the compartment H', by closing or narrowing one throat or the other; or it may be a Venetian blind, by 60c which a similar result would be accomplished, or a belt, such as hereinafter described.

At the tail the screen may discharge into an ordinary spout, n; but in order to submit the tailings themselves to the action of air-currents 65 to remove any remaining particles of dust or fine impurities and to grade them according to their weight, I bifurcate this spout and cause

it to discharge on either side of the machine past an air-port into a chamber, p, which communicates through a trunk, p', with the suc- 70 tions-chamber. A series of sub-spouts, q, are arranged in the tailings-chamber, between the air-port and air-trunk below the line of draft, to receive the tailings graded by the air-current; and gates q' are provided between each 75 sub-spout, whereby the number of grades may be determined. The intensity of the draft through the tailings-chamber may be controlled by means of a gate, o', placed over the air-port o, and another gate, p'', may be pro- 80 vided in the trunk p', whereby the draft may be cut off altogether.

For the sake of compactness of build the sides of the chest H' are caused to converge slightly, as shown in Figs. 2 and 3, to afford 85 space at the bottom of the machine for the trunk p' to be laid between them and the vertical side walls of the casing. Air may gain access to the ports of the chest H' through openings r in the sides of the machine, or from 90 beneath the spout, or from both sources, according to the exigencies of the structure.

In case a shaker is used in place of the sta- 95 tionary screen shown, it will be placed at the usual angle given to shakers in purifying-ma- chines, and the outlines of the chamber H and chest H' will be correspondingly modified; but the arrangement and action of the mechanism will not be essentially changed. The cam-shaft c' will afford convenient means for 100 driving the shaker.

When it is desired to use a beater or dis- 105 integrator upon the chop as it falls from the rolls or from whatever delivery mechanism may be employed, I find it convenient to adopt the arrangement shown in Fig. 4, placing the upper serial air ports and gates, e' f', at the outer end of compartment H, so as to turn the whole compartment into the chop-chamber, and substituting a slatted belt, S, the width of the 110 compartment, and driven, as indicated by the arrow, for the board m.

The beater N, which may be a stationary or 115 revolving cage, as described in my application hereinbefore referred to, or of any other suitable construction, will be placed about centrally above the belt in the path of the stream of chop as it enters the chop-chamber, so as to 120 strike it, lighten it up, and scatter it through said chamber, exposing it to the full strength of the air-currents by which the flour and dust will be taken out.

The middlings as they settle upon the belt 125 will be carried up and deposited upon the head of the screen or shaker over which they will travel, as in the first-described construction, being shut off from the drafts by the lower face of the belt, which performs the same function in this respect as the board which it sup- 130 plants.

The chop-grader proper, as I have described it, being inclosed in a square case fitting into the ordinary frame-work of the roller-mill, is adapted to be removed integrally therefrom

and used independent thereof with a hopper or other device for delivering chop, while the mill can be turned to other reductions.

I claim as my invention—

1. The combination, with the screen and the converging chest and wind-trunk beneath, of the bifurcated spout, the tailings-chambers and their external air-ports, the series of sub-spouts, and the trunks laid under the converging sides of the chest and communicating with the suction-chamber.

2. The combination of the crushing-rollers, the inclined screen, the diaphragm above said

screen, the chest and wind-trunk beneath the screen, the fan exhausting from said chest, and 15 the bifurcated tailings-spout and its series of sub-spouts, also exhausted by said fan.

3. The combination of the crushing-rollers, the rotary beater, the inclined apron beneath said beater, the inclined screen beneath the 20 apron, the chest and wind-trunk beneath the screen, the suction-fan, and the tailings-spout.
